FRONT PANEL OF A HOOD PORTION OF A TYPEWRITER CASING

Otto Winter, Wilhelmshaven, Germany, assignor to Olympia Werke AG., Wilhelmshaven, Germany,
a corporation of Germany

Filed June 26, 1961, Ser. No. 65,708

Term of patent 3½ years

(Cl. D64—11)

The figure on the drawing is a perspective view of a front panel of a hood portion of a typewriter casing showing my new design.

The parts of the casing indicated in broken lines are for illustrative purposes only.

I claim:

The ornamental design for a front panel of a hood portion of a typewriter casing, as shown and described.
